UNITED STATES PATENT OFFICE.

HAROLD W. WISHART, OF CLINTON, IOWA, ASSIGNOR, BY MESNE ASSIGNMENTS, TO CLIMAX ENGINEERING COMPANY, OF CLINTON, IOWA, A CORPORATION OF DELAWARE

ROTARY COMPRESSOR.

Application filed February 2, 1922. Serial No. 533,736.

To all whom it may concern:

Be it known that I, HAROLD W. WISHART, a citizen of the United States, and a resident of the city of Clinton, in the county of Clinton and State of Iowa, have invented certain new and useful Improvements in a Rotary Compressor; and I do hereby declare that the following is a full, clear, and exact description of the same, reference being had to the accompanying drawings, and to the numerals of reference marked thereon, which form a part of this specification.

This invention relates more particularly to an improved type of rotary compressor wherein an air cooled casing is arranged to permit a gas to enter an eccentrically operated piston and flow into a space between the piston and a stationary casing containing the piston, said gas adapted to be compressed and then forced out of openings in said casing into a bath of lubricant contained within the casing and from which the compressed gas is permitted to escape through a container having separating means therein for separating the lubricant from the escaping gas.

It is an object of this invention to provide a rotary compressor wherein a cylinder is held in position by pressure means, said cylinder having bearings mounted therein supporting a positively lubricated eccentric shaft which acts to operate a piston within the cylinder to compress a gas and then discharge the compressed gas into a bath of lubricant contained within a casing enclosing the cylinder.

It is also an object of the invention to construct a rotary compressor wherein a cylinder is mounted, said cylinder provided with bearings supporting an eccentric shaft which is adapted to be driven by a drive shaft constructed to insure positive lubrication thereof and adapted when operating to cause the eccentric shaft to operate a piston within the cylinder to compress a gas and then discharge the compressed gas through a bath of lubricant out of the compressor between baffle plates.

Another object of the invention is to provide a compressor with an improved drive shaft constructed to insure positive lubrication of the drive shaft mechanisms as well as the lubrication of an eccentric shaft and bearings supported thereon in position

to have a rotatable compressor mechanism engaged on one of the bearings receive a drive from the eccentric shaft to compress a gas and discharge the same from the compressor.

A further object of the invention is to provide a compressor wherein the compressing mechanisms are disposed within a casing containing a bath of lubricant and are actuated by means of a drive shaft on which an exhaust fan is mounted to cause a circulation of air through a housing surrounding the compressor casing for the purpose of cooling the compressor.

It is furthermore an object of the invention to provide a compressor wherein an air exhaust fan is engaged on the drive shaft for the purpose of drawing air through a housing surrounding a compressor casing, said casing containing a bath of lubricant for the purpose of insuring positive and proper lubrication of the compressing mechanisms, said lubricant also serving as a sealing and cooling medium for the compressing mechanisms operating within the casing and driven by said drive shaft.

It is a further object of this invention to construct a compressor having a casing containing a sealing and cooling lubricant wherein a cylinder is held in position and contains a piston adapted to be actuated by an eccentric engaged on a drive shaft, the bearings of which are constructed to insure positive lubrication thereof by lubricant from said casing entering the cylinder through a screening means.

Still another object of the invention is the construction of a compressor or wherein the operating mechanisms are submerged in a bath of lubricant within a casing having a large radiating surface to permit rapid cooling thereof by means of a fan on the compressor drive shaft which acts to induce a draft of air through a housing surrounding the casing.

It is an important object of this invention to provide a compressor wherein an eccentrically operated piston is adapted to have contact with the inner peripheral surface of a stationary cylinder at all times, and is provided with a blade operable in a rocker member supported in said cylinder.

It is also an object of the invention to construct a rotary compressor wherein an eccentrically operated member within a

cylinder has a grooved vane or blade radially secured thereto for slidable engagement with a slotted rocker which is movably engaged within a recess of said cylinder, said 5 eccentrically operated member acting to discharge a compressed medium from between the cylinder and said eccentrically operated member into a bath of lubricant from which the compressed medium is permitted to 10 escape.

It is an important object of this invention to provide an improved type of rotary compressor adapted to compress a medium and then discharge the same through a bath 15 of lubricant contained within a cooled casing enclosing the compressing mechanisms.

Other and further important objects of this invention will be apparent from the disclosures in the drawings and specifications.

20 The invention (in a preferred form) is illustrated in the drawings and hereinafter more fully described.

On the drawings:

Figure 1 is an end elevation, partly broken 25 away, of a compressor embodying the principles of this invention.

Figure 2 is an enlarged section taken on line 2—2 of Figure 1.

Figure 3 is a section taken on line 3—3 30 of Figure 2 showing the piston blade in closed position.

Figure 4 is a similar section illustrating the piston blade in open position and the piston at the end of half of its movement.

35 Figure 5 is an enlarged detail section taken on line 5—5 of Figure 3.

Figure 6 is an enlarged fragmentary longitudinal section of the drive shaft, the eccentric shaft and the drive shaft bearing.

40 As shown on the drawings:

The improved rotary compressor comprises an outer housing 1 provided with end openings 2 and 3 and having a top opening at 4. Mounted within the housing 1 is a metal 45 casing 5 provided with a cover or head 6 which is secured to the casing by bolts 7 or other suitable means. The casing 5 is provided with a plurality of webs, ribs or vanes 8 which are formed on the exterior of said 50 casing to increase the radiating surface thereof. Integrally formed within the casing 5 is a stop 5^a to prevent rotation of the compressor cylinder hereinafter described.

The casing cover 6 is also provided with 55 webs, ribs or vanes 9. Formed upon the top of the casing 6 is an internally threaded flange 10 having threaded therein the lower open end of a box or flue 11 having a plurality of staggered baffle plates 12 therein. An 60 outlet or discharge pipe 13 has one end thereof connected with the flue 11 while the other end is connected with any suitable container for receiving compressed gas from the compressor. A plurality of outlet ports 65 14 are provided in the top of the casing 5

and connect the interior of said casing with the interior of the flue 11. The top portion of the casing 5 having the ports 14 therein serves as the first baffle plate.

The casing 5 is provided with an intake 70 passage 15 into which one end of an inlet pipe 16 is secured to permit a gas to be compressed to enter the compressor. Integrally formed axially in the casing 5 is a hub or sleeve 17 the outer end of which 75 projects through the housing opening 2. The intake passage 15 communicates with the interior of the sleeve 17. A bearing 18 is disposed within the sleeve 17 to the outside of the inner end of the intake passage 80 15, and is provided with a spiral lubricating groove 18^a. The bearing 18 at one end is provided with an integral flange. Axially positioned within the casing 5 is a drive shaft comprising an enlarged shank 19, having integrally formed on one end thereof a solid extension 20 and on the other or inner end a tubular extension 21. The drive shaft shank 19 is provided with an exterior lubricating groove 22 which communicates 90 through a radial passage 23 with a passage or chamber 24 provided within the shaft shank and forming a continuation of the passage in the inner shaft extension 21. The drive shaft shank 19 engages in the 95 bearing 18 with the shank shoulder seated against the flange of the bearing. The outer shaft extension 20 projecting out of the casing sleeve 17 and through a washer 25 engages in the outer end of said casing sleeve. 100 As illustrated in Figure 2, the outer drive shaft extension 20 is provided with a throw rib 26 positioned between the bearing 18 and the washer 25.

Keyed or otherwise rigidly secured on the 105 projecting drive shaft extension 20 adjacent the housing opening 2 is a fly-wheel 27 on the inner face of which a plurality of exhaust fan blades 28 are integrally formed. The shaft 20 is adapted to be driven by a 110 motor shaft connected with the fly-wheel 27 by means of a flexible coupling. The motor shaft and the flexible coupling are not illustrated.

Engaged around the inner floating drive 115 shaft extension 21 is an eccentric shaft comprising a collar or sleeve 29 having an eccentric 30 integrally formed thereon intermediate the ends thereof. One end of the shaft 29 is provided with clutch teeth to 120 coact with clutch teeth formed on the inner end of the drive shaft shank 19. A plurality of longitudinal grooves 31 are provided in the sleeve 29 of the eccentric shaft permitting gas mixed with lubricant to pass from 125 passage 15 into the piston.

Mounted on the eccentric shaft 29 are two 130 bearings 32. A large bearing 33 is mounted on the eccentric 30 between the bearings 32. Positioned within the casing 5 and sup-

porting the bearings 32 is a cylinder comprising two side plates 34 and 34^a separated by a spacing ring 35. Bolts 36 are used to rigidly hold the side plates secured on opposite sides of the spacing rings 35. The cylinder side plates 34 and 34^a and the spacer ring 35 are respectively provided with integral extensions 37 and 38 having a recess 39 therein. Movable seated in the recess 39 is a cylindrical rocker 40. The rocker 40 is provided with a diametric cylindrical opening in which a vane or blade 41 is slidably engaged. The inner end of the blade 41 is rounded and projects into a curved recess provided in the periphery of a rotor or piston 42. The piston 42 is ring shaped and is mounted upon the bearing 33 within the cylinder spacer ring 35 and between the side plates 34 and 34^a. The blade 41 is axially passaged and is rigidly held seated in the piston recess by means of a bolt 43 as clearly illustrated in Figures 3 and 4. The piston 42 is provided with a port or passage 44 to permit a medium such as gas to flow from the interior of the piston into the crescent shaped compression chamber 45 formed between the cylinder and the piston. The blade 41 is cut away at 46 to afford an outlet passage, which communicates with a discharge passage 47 in the spacer ring extension 38.

The cylinder side plate 34^a adjacent the casing cover 6 is provided with a flange ring 48 around which one end of a heavy coiled spring 49 is engaged. The outer end of the spring 49 seats in a pocket formed in the inner side of the casing cover 6. The spring 49 acts to hold the cylinder in place pressed against a casing ring flange 50 integrally formed within the casing 5. The cylinder is kept from vibrating by the action of the spring 49 and the stop 5^a with the oil 64 serving to obviate wear on said stop by the cylinder. Seated within the ring flange 48 of the cylinder side plate 34^a is a filter screen 51 held in place by a retaining ring 52. Referring to Figure 6 a bearing ball 53 is engaged within the drive shaft shank and is held in place by a block 54 or head 54. A spring 55 is disposed within the passage 24 of the drive shaft shank and has one end thereof engaged against the block 54 and the other end engaged around the reduced end 56 of a tube 57. A threaded head 58 is integrally formed on one end of the tube 57 and is threaded into an opening provided in the cylinder side plate 34^a. A lubricating passage 59 is provided longitudinally in the tube 57 and has one end thereof communicating with a tapered or restricted orifice 60 provided in a small plate 61 seated in the head 58. A thin plate 61^a is positioned adjacent the plate 61 and has a very small central opening therein. A washer 62 and a packing

ring 63 are secured in the opening of the side plate 34^a to hold the plates 61 and 61^a in place. A bath of lubricant such as oil or glycerine 64 is contained within the casing 5.

70

The operation is as follows:

The compressor is operated by connecting the drive shaft 20 and the fly-wheel 27 with a motor or other suitable driving means. Rotation of the drive shaft 75 19-20-21 acts to rotate the eccentric shaft 29 and the eccentric 30 forming a part thereof. The piston 42 on the bearing 33 is actuated by the eccentric which causes the piston to have a continuous rolling contact 80 with the inner surface of the cylinder spacer ring 35. During the operation of the piston 42 the blade 41 has a sliding movement with respect to the rocker 40. A gas to be compressed is admitted through the inlet 85 pipe 16 and enters the compressor casing through the passage 15 and passes through the grooves 31 to fill the space within the piston 42. From the piston 42 the gas passes through the piston port or passage 90 44. Referring to Figure 3, the eccentric 30 rotates to actuate the piston 42 in a clockwise direction thereby gradually sliding or drawing the blade 41 out of the rocker 40 as the point of contact between the piston 95 and the inner peripheral surface of the cylinder advances with the movement of the piston by the rotation of said eccentric. The piston port 44 is thus opened to permit the gas within the piston to start to flow into 100 the crescent-shaped compression chamber 45^a being formed on the intake side of the piston blade 41. As the piston moves from the position shown in Figure 3, the blade outlet opening 46 is gradually opened. Gas 105 trapped within the compression chamber 45 is gradually compressed as the chamber 45 decreases in size with the increase in size of the filling chamber 45^a.

With the opening of the blade outlet 110 opening 46, the compressed gas in the chamber 45 is forced through the cylinder outlet opening 47 and is discharged into the bath of lubricant 64 within the casing 5. The novel arrangement of the compressing 115 mechanism causes the positive ejection of the compressed gases from the cylinder thereby permitting the compression chamber to be completely filled with a new charge with each operation of the piston.

As the compressed gases are discharged into the casing 5, they mix with the lubricant 64 and travel upwardly therethrough into the upper portion of the casing and escape through the outlet ports 14 into the 125 flue 11. In passing into the flue 11, the compressed gases strike and pass between the baffle plates 12 thereby causing any particles of oil carried by the escaping gases to be deposited. The compressed gases after 130

passing the baffle plates escape through the pipe 13 to enter a tank or other container.

During the operation of the compressor the fly-wheel 27 is rotated, thereby causing 5 the fan blades 28 to exhaust or draw the air through the housing 1 around the casing 5. The vanes 8 and 9 on the casing 5—6 increase the radiating surface thereof and permit the draft of air through the housing 10 to cool the casing and the operating mechanisms therein. The bath of lubricant in the casing 5 also acts as a cooling medium for the operating mechanism.

As illustrated in Figure 2, the cylinder 15 within the casing is held in place by the coiled spring 49 which acts to hold the cylinder in tight contact with the casing flange 50 thus separating the compression chamber in casing 5 from suction gases 20 within the piston. The cylinder is also engaged on the inner end of the casing sleeve 17. The drive shaft has the shank 19 thereof seated in the bearing 18 while the inner extension 21 of the shaft substantially floats 25 and has the eccentric shaft 29—30 surrounding the same to be rotated thereby by means of the clutch teeth formed on said shank 19 and on said extension 29. To insure positive lubrication of the rotating 30 driving mechanisms, lubricant from the casing is permitted to flow through the cylinder screen 51. The screen prevents particles of grit or foreign matter from entering the space between the cylinder and the screen. 35 The filtered lubricant passes through the members 63 and 62 and under the discharge pressure within the casing is forced through the small aperture in the plate 61^a and enters the restricted opening 60. The lubricant then passes through the tube passage 59 into the passage 24 around the bearing ball 53, the block 54, the spring 55 and the tube 57 all of which are properly lubricated at all times. Lubricant from the drive 40 shaft passage 24 is expelled through the shaft port 23 and passes along the groove 22 to lubricate the shaft shank 19 as it operates in the bearing 18.

The bearing ball 53 acts to hold the shoulder of the shaft shank 19 pressed tightly 50 against the flange of the bearing 18.

Lubricant expelled from the edges of groove 22 mix with the suction gases entering through the passage 15 and thus the 55 lubricant is carried to all parts of the operating mechanism affording a seal preventing the leakage of gases from the compressor. Lubricant from the shaft passage 24 also passes out of the inner open end of the 60 shaft extension 21 into the bearing chamber of the cylinder. The bearings 32 and 33 are thus properly lubricated at all times. The lubricant mixed with the gases within the cylinder acts as a liquid seal preventing the 65 leakage of gases.

It will, of course, be understood that the cylinder 34—35—34^a may be held in place on the sleeve 17 and against the flange 50 directly by the casing cover plate or by other suitable means in place of by the 70 spring 49.

I am aware that numerous details of construction may be varied through a wide range without departing from the principles of this invention, and I therefore do 75 not purpose limiting the patent granted otherwise than necessitated by the prior art.

I claim as my invention:

1. A rotary compressor comprising a casing, a cylinder therein, means comprising a coiled spring for holding said cylinder in place, a rocker in said cylinder, a piston in said cylinder, a blade on said piston slidably engaged in said rocker, and eccentric means for operating said piston to cause the compression of a medium by the compressor. 80

2. A compressor comprising a casing having an intake passage and outlet ports therein, a cylinder in said casing, a cover secured to the casing to enclose said cylinder, means between the cylinder and cover for holding said cylinder secured in position, a piston in said cylinder, a drive shaft projecting into said casing and cylinder, an eccentric member in said cylinder actuated 95 by said drive shaft, bearing members between said eccentric member and said cylinder, a bearing member on said eccentric member within said piston for operating the piston to cause a medium entering said intake passage to be compressed between the cylinder and said piston, a slotted member seated in said cylinder, and a blade secured to said piston and slidably engaged with said slotted member, said slotted member having a passage to permit the compressed medium to escape from the cylinder and be discharged through the casing outlet ports. 100

3. A compressor comprising a casing, a cylinder therein, a resilient member for holding the cylinder in place, a stop integrally formed in the casing for holding the cylinder against rotation, eccentrically operated means in said cylinder for compressing a medium entering the cylinder, and drive means for driving said eccentrically operated means. 110

4. A compressor embracing a casing, a compressing device therein, and resilient 120 means engaged between said casing and said device for holding the device in operating position.

5. A compressor comprising a casing, a cylinder secured therein, a piston in said cylinder contacting the same at one point to form a crescent shaped chamber, a rocker seated in said cylinder, a blade bolted to said piston and slidably engaged in said rocker, an eccentric for operating the piston, 125 130

a drive mechanism and clutch members between the eccentric and said drive mechanism.

6. A compressor comprising a casing, a cylinder held therein against rotation, a drive shaft journalled in said casing and projecting into said cylinder, an eccentric shaft telescoping with the drive shaft and connected to be driven thereby, and a piston 10 in said cylinder supported on said eccentric shaft and actuated thereby to cause compression of a medium between the cylinder and said piston.

7. A compressor comprising a casing having a lubricant therein, a cylinder in said casing partially submerged in said lubricant, resilient means in the casing for holding the cylinder in place, drive mechanisms projecting into the casing and into said 20 cylinder, said drive mechanisms having grooves and passages therein to insure positive lubrication thereof, a lubricant inlet tube projecting into the drive mechanisms, screens for filtering the lubricant before entering said tube, an eccentric operable by said drive mechanisms, a bearing thereon, and a piston in said cylinder supported on said bearing.

8. The combination with a casing containing a bath of lubricant, of compressing mechanisms therein, means for driving the same to cause the mechanisms to compress a medium and discharge the same into the bath of lubricant, and means operable by said driving means for cooling the casing and the mechanisms therein.

9. The combination with a casing containing a bath of lubricant, of a housing surrounding the casing, means within the casing for compressing a medium and discharging the same when compressed into the bath of lubricant, a driving mechanism for operating said compressing means, a fan mounted on said driving mechanism for causing a draft of air through the housing to cool said casing and the compressing means therein, a flue mounted on said casing projecting out of said housing to permit the escape of the compressed medium after the same passes through the lubricant, and baffle members secured in said flue to separate oil from the escaping compressed medium.

10. The combination with a compressor, of interfitting shafts for driving the same, and means mounted on one of said shafts and operable thereby for cooling the compressor.

11. The combination with a compressor, of a drive means for operating the same, a fly-wheel secured on said drive means and operable therewith, and fan blades on said fly-wheel to cause cooling of the compressor when operating.

12. A compressor comprising a casing having intake and outlet openings therein,

a sleeve formed on the casing and projecting therein, a flange in said casing, a compressor device positioned in said casing adapted to draw a medium through said casing intake opening, compress the medium and then discharge the same through said outlet openings, means in the casing for holding the compressor device engaged on said sleeve and in contact with said flange, an eccentric for operating the compressor device, and drive means for rotating said eccentric.

13. A compressor comprising a casing, a cylinder therein, means for holding the cylinder in position, a compressor mechanism on said cylinder, a passaged drive shaft in said casing projecting into said cylinder, a bearing for said drive shaft having a spiral lubricating groove therein, a tube secured in said cylinder and projecting into the passaged drive shaft, a bearing ball in said drive shaft, a block in said drive shaft between the bearing ball and said tube, a spring between the block and said passaged member for holding the block in contact with the bearing ball and also holding the drive shaft pressed against a shoulder of said bearing, an eccentric shaft operated by the drive shaft within said cylinder, and bearings on said eccentric shaft supported by the cylinder.

14. A compressor comprising a casing, a cylinder supported therein, a piston in said cylinder, a passaged drive shaft journalled in said casing and projecting into said cylinder, a tube secured in said cylinder and projecting into said drive shaft, bearing members between said tube and said drive shaft, means for lubricating the bearing members in said drive shaft, a second shaft driven by said drive shaft within the cylinder, bearing members between said second shaft and said cylinder, an eccentric formed on said second shaft, and a bearing member between said eccentric and said piston.

15. The combination with a rotary compressor, of a drive mechanism therefor comprising a passaged shaft shank having a peripheral lubricating groove and a port connecting said groove with the passage in said shank, a solid shaft extension on one end of said shank, a passaged shaft extension on the other end of said shank, a support having an opening therein, a tube secured in said support opening and projecting axially into said passaged shaft extension, a bearing ball in said shaft shank, a block in said shaft shank, a spring between said tube and said block to cause the block to hold the bearing ball in bearing position, a disk seated in the outer end of said tube and having an orifice therein communicating with the passage in said tube, a plate adjacent said disk having an aperture therein, members for holding the disk and plate.

- cured in place, and a screen in said support for filtering a lubricant before entering the drive mechanism through said apertured plate and the orifice in said disk.
- 8 16. The combination with a compressor, of interfitting shafts therein, and an eccentric integral with one of said shafts adapted to be actuated by the other shaft to cause operation of the compressor.
- 10 17. The combination with a compressor, of a driven shaft section supporting the same, a driving shaft section interfitting the driven shaft section and operating the same, and a fan mounted on the driving shaft section and driven thereby for cooling the compressor when operating.
18. The combination with a compressor and a fan for cooling the same, of a fly-wheel forming part of the fan, a driving shaft supporting the fly-wheel and fan, a 20 driven shaft interfitting the driving shaft to receive a drive therefrom to cause operation of the compressor, and means for positively lubricating the compressor, said driving shaft and the driven shaft. 25

In testimony whereof I have hereunto subscribed my name in the presence of two subscribing witnesses.

HAROLD W. WISHART.
